PLANTER

Louis E. Charpentier, Leominster, Mass., assignor to Gilbert Josephson, New Rochelle, N.Y.

Filed Mar. 13, 1961, Ser. No. 64,267

Term of patent 14 years

(Cl. D35—3)

FIG. 1

FIG. 2

FIG. 3

FIG. 4

FIG. 1 is a front perspective view of a planter showing my new design;

FIG. 2 is a side elevational view thereof;

FIG. 3 is an enlarged fragmentary view of the portion of the planter shown in area 3 in FIG. 1; and

FIG. 4 is an enlarged fragmentary view of the portion of the planter shown in area 4 in FIG. 1.

I claim:

The ornamental design for a planter, substantially as shown.
